(57) **CLAIM**

The ornamental design for a charging box for wireless earphones, as shown and described.

DESCRIPTION

FIG. 1 is a front, top, left side perspective view of a charging box for wireless earphones, showing my new design closed in a first configuration;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a top, front, left side perspective view of the charger for earphones of FIG. 1, shown open in a condition of use in a second configuration.

The broken lines in the drawings depict portions of the charging box for wireless earphones that form no part of the claimed design. In FIG. 9, the broken lines showing earphones depict environmental subject matter only, and form no part of the claimed design.
